Primary Examiner — Ricky Pham

(57) **CLAIM**

The ornamental design for transformable rotating broiling rack, as shown and described.

DESCRIPTION

1. Transformable rotating broiling rack

1.1 : Perspective

1.2 : Front

1.3 : Back

1.4 : Left

1.5 : Top

1.6 : Perspective view of transformed product

1.7 : Side view of transformed product

1 Claim, 7 Drawing Sheets(56)
